UNITED STATES PATENT OFFICE.

HARRY C. CLAY, OF COLUMBUS, INDIANA, ASSIGNOR TO EMERSON-BRANTINGHAM COMPANY, OF ROCKFORD, ILLINOIS, A CORPORATION OF ILLINOIS.

BALING-PRESS.

1,308,397.

Specification of Letters Patent.

Patented July 1, 1919.

Original application filed September 18, 1916, Serial No. 120,870. Divided and this application filed January 29, 1918. Serial No. 214,369.

To all whom it may concern:

Be it known that I, HARRY C. CLAY, a citizen of the United States, residing at Columbus, in the county of Bartholomew and State 5 of Indiana, have invented certain new and useful Improvements in Baling-Presses, of which the following is a specification.

This invention, a division of my application, Serial No. 120,870, filed Sept. 18, 1916, 10 for improvements in baling presses, pertains to the manner in which a division block, which is inserted between the bales, is placed into and out of set position by a block guide and is moved by a block inserter into the 15 baling chamber.

It is customary to employ a block guide adapted to receive a division block in a position at one side of the feed opening of a baling chamber and movable into a position 20 in alignment with the feed opening in the path of a block inserter generally attached to the feed head so that in the feed stroke of the latter the inserter member will strike the block and move it into the baling chamber. 25 If through carelessness or negligence on the part of the operator in not moving the block guide into set position at the proper time with relation to the movement of the feed head, or in not fully moving the block guide 30 to set position, or because an accidental obstruction prevents moving the block guide fully to set position, the block inserter as constructed prior to my invention will not properly engage the block. As a consequence, 35 the parts will be jammed or broken to various degrees, sometimes causing considerable damage to the feed head and operating mechanism.

In the present invention I have aimed to 40 prevent the occurrence of such an accident, and to this end I have provided a block holder or guide and a block inserter of novel construction which insures safety in operation and absolutely prevents any jamming 45 or breaking of parts as might be occasioned by not properly or timely placing the block in set position.

In this connection, I have also provided 50 an improved tucker, which aside from its regular function, coöperates with the block holder in an advantageous manner as will be described later.

Referring to the drawings:

Figure 1 is a longitudinal sectional view

substantially through a baling press embodying my improvements, showing the feed head at the end of its feeding stroke;

Fig. 2, a fragmentary side elevation showing the block inserter properly engaging a block during the feed stroke;

Fig. 3, a fragmentary side elevation illustrating a division block having been improperly positioned, and the consequent action, which avoids jamming or breakage; and

Fig. 4, a fragmentary perspective view of the block guide and associated parts.

While this invention relates particularly to the means for guiding and inserting the division blocks, I have illustrated briefly in the drawings one form of the principal 70 parts of a baling press in order that a clear understanding of the operation may be had. These include a suitable frame 5 providing a baling chamber 6, a compressing plunger 7 operated directly by the main drive gears 8, 75 which are driven by a suitable engine 9 through the agency of gearing 11, and a feed head 12 adapted to be moved into and out of the baling chamber through the feed opening 13 in timed relation with the compressing plunger. Since the operation of the compressing plunger and feed head is well understood in the art I will simply add that while any suitable operating mechanism 80 may be employed with my present improvements, the means shown for oscillating the feed head consists of circular cams 14 fixed to the main drive gears and shaped to swing the feed head 12 up and down about the pivots 15 of the carrying links 16 at the 85 proper intervals, through the agency of the connection designated by character 17. The construction and operation of the foregoing mechanism is more fully described in my 90 companion application mentioned above. 95

The tucker employed for forming an even top to the bale by tucking or folding in the loose ends of the hay after the plunger has been withdrawn is in the form of an arcuate body 18 extending transversely across one 100 end of the feed opening 13 as shown clearly in Fig. 1 and having arms 19 formed at its end and pivotally mounted on studs 21 secured to the outer sides of the frame. Arcuate guards 22 bolted to the top of the 105 frame overlie the adjacent portions of the tucker so as to prevent chaff, hay and foreign particles from getting between the

frame and tucker and interfering with the operation of the same. A yielding force is employed to constantly urge the tucker downwardly, that is, in a clockwise direction viewing Fig. 1, to a position limited by abutment of the ends of the tucker against the top of the frame. This force is obtained by means of contractile springs 23 connecting the free ends of the arms 19 to the frame as shown clearly in Fig. 4. When a large quantity of hay is compressed, the tucker will be raised against the tension of the spring 23 and when the plunger is withdrawn the tucker will automatically fold the loose hay into the compressing chamber.

The dividing block guide and dropper of novel construction and operation will now be described. The block designated by reference character 24 may be of any suitable construction and is shown as being built up of a plurality of boards secured together by iron cleats so as to provide a durable structure. The block holding and guiding means, the construction of which is best shown in Fig. 4, consists of a pair of parallel channel guides 25 rigidly secured to a cross channel bar 26 to the ends of which are secured supporting arms 27 pivotally mounted on the studs 21 at the outer sides of the tucker arms 19. The block guide is shown in an operative or set position in Fig. 4 in which the guides 25 are vertically disposed above the feed opening 13, said guide being merely held by gravity in this position with its feet 28 resting on the top of the guard brackets 22. The block guide may be swung on its pivot from this position by grasping one of the handles or bars 29 secured to the guides 25 and swinging them to an upright position as indicated in dotted lines in Fig. 1. The block may be inserted in the guide when it is in this block-receiving position and at the proper time, when a bale has been compressed, the operator will swing the guide to upright position from which the block may be ejected from the guide by a dropper carried by the feeder head as will be presently described. Means for preventing displacement of the block from the guide until the block is ejected by the dropper, consists of a yielding stop 31 pivoted intermediate its ends at 32 to the underside of the cross bar 26 and constantly urged in one direction by a spring 33 operating on one end of the stop to carry its opposite end into the path of a block inserted in the guide. This stop when in the position shown in Fig. 1, serves as a yielding detent to prevent the block from dropping and is adapted to yield when sufficient downward pressure is applied to the block thereby permitting the same to be moved down through the guide. It will be noted that when the block guide is in block-receiving position, the lower end 65 of the stop 31 will engage the arcuate wing

34 of the tucker, thereby causing the stop to positively limit the extent to which the block may be inserted into the guide. Thus it is impossible when setting a block to move it too far into the guide but when the guide 70 is moved to operative or set position the positive stop automatically becomes a yielding detent. It will be noted that when the block guide is in receiving position the tucker may operate back and forth without 75 disturbing the locking effect it has on the stop 31.

The block will be ejected from the guide and dropped into the compressing chamber to form a division between two bales, by the 80 action of a dropper carried by the feeder head. This dropper best shown in Fig. 1, is in the form of a pendant arm 35 pivotally connected at 36 to the feeder head and urged outwardly by an expansion spring 37 interposed between the head and arm, to a position limited by a bolt 38 pivotally connected to the free end of arm 35, passing loosely through an aperture in the feed head and provided with an adjustable head or stop 39 85 for limiting the outward movement of the arm. As shown in Fig. 2, when the feeder head descends and a block is properly supported in set position it will be engaged by the dropper 35 and forced downwardly into the compressing chamber, movement of the block toward the plunger while in the chamber being prevented by the stops 41 projecting into the chamber from the side walls thereof. It sometimes happens that an operator will negligently or carelessly swing the block guide toward the intended set position at the wrong time, that is, after the dropper has passed below the top of the block. This ordinarily would result in a 95 jam or break of more or less serious nature, but with the provision of my improvements the dropper will simply yield and pass idly by the block. Upon the following feed stroke the block, when positioned fully into 100 set position, will be properly engaged and moved into the baling chamber. Such improper positioning of the block guide often occurs from an accidental obstruction, such for example as an accumulation of hay on 115 the castings 22 or above the feed opening, which prevents moving the block guide fully to set position. An improper position of the block guide is shown in Fig. 3 and under this condition when the feeder head descends 120 the dropper will simply strike the adjacent inclined side of the block and will yield while passing downwardly across the face of the block so as not to injure or damage either the dropper, the feeder head or the 125 block holding and guiding means.

When the block has been dropped into the compressing chamber the next compressing stroke of the plunger will move the block into the baling chamber and past the in- 130

wardly projecting ends of spring-pressed stops 42 which prevent the block from being forced back into the compressing chamber by the expanding action of the bale. A pair of these stops 42 project through each side wall and, as shown in Fig. 4, are pivotally mounted and yieldingly held in stopping position by means of expansion springs 43.

I claim:

- 10 1. In a baling press, the combination of a division block guide comprising a frame adapted to receive a division block and movable to carry the block from a receiving position to a set position, a spring pressed 45 detent or stop carried by the frame and serving to yieldingly oppose passage of the block therethrough, and means for causing said detent to act as a positive stop when the block guide is in receiving position and permitting the detent to function as a yieldable 50 stop to allow the block to be passed through the guide when the latter is in said set position.
- 15 2. In a baling press, the combination of a pivotally mounted block guide movable from a block-receiving to a block-dropping position, a spring pressed detent carried by the 55 guide for yieldingly opposing passage of a block therethrough, and an abutment with 60 which the detent engages when the guide is in block-receiving position causing the yielding detent to function as a positive stop for preventing passage of a block through the 65 guide.
- 20 3. In a baling press, the combination of a 70 block guide and a tucker co-axially mounted,

and a spring pressed detent mounted on the guide for yieldingly opposing passage of a block therethrough, said detent being controlled by the tucker so as to positively prevent passage of a block through the guide 40 when the latter is in block-receiving position and to yieldingly oppose such passage when the guide is in inoperative or set position.

4. In a baling press, the combination of a 45 block guide and a tucker mounted in juxtaposition, the block guide being movable from a block-receiving to a block-dropping position, and means for yieldingly opposing passage of a block through the guide when the 50 latter is in block-dropping position and influenced by the tucker when the guide is in block-receiving position to positively prevent passage of a block through the guide.

5. In a baling press, a division block inserter comprising a feed head movable into and out of the baling chamber, a block-dropper pivotally connected at its upper end to the feed head and inclined downwardly and away from the feed head so that the 60 lower or block-engaging end of the block-dropper is substantially spaced from the feed head, a spring constantly urging the lower end of the block dropper away from the feed head, and a rigid member pivotally 65 connected to the lower portion of the block-dropper and loosely passing through an aperture in the feed head and having an abutment on its end projecting through said aperture for limiting movement of the block-dropper under the influence of the spring. 70
